UNITED STATES PATENT OFFICE

WALTER M. CROSS, OF KANSAS CITY, MISSOURI, ASSIGNOR TO CROSS COAL-O-MATIC COMPANY, OF KANSAS CITY, MISSOURI, A CORPORATION OF MISSOURI

HEATING-SYSTEM CONTROL

Application filed January 31, 1927. Serial No. 164,953.

This invention relates to improvements in a heating system control and refers more particularly to a dual system of control; one phase of the heating system operating the fuel feed and force draft mechanism and depending upon its actuation by variations in the room temperature of the dwelling to be heated; the other control functioning the fuel feed and force draft by predetermined minimum temperatures either in the furnace or combustion pot or the temperature of the water circulating through the boiler or hot water system.

The control is in connection with an automatic stoker and furnace set-up which is operated either at maximum conditions of efficiency or under optimum operating or combustion conditions on one hand and bank fire conditions of operation on the other. In brief the control is such that as normally operated the heat supplied to the dwelling will be dependent primarily upon the thermostatic control functioned by the room temperature, while the secondary control, either in the combustion pot or actuated by the temperature of the boiler water will serve primarily to keep the fire alive or prevent extinguishment when the system is not being drawn upon for heat to the dwelling.

This application is a continuation in so far as the control is concerned of my previous applications, Serial No. 44,604, filed July 18, 1925, and Serial No. 147,667, filed Nov. 11, 1926.

Fig. 1 of the drawing depicts a sectional side view of the end feed stoker showing the manner of installing the control in connection with a steam boiler setting.

Fig. 2 shows the electrical control system. Referring to the drawings, at 1 is shown a common type of furnace setting, in which are positioned the flue tubes 2, water being circulated around the flues in the boiler 3. The combustion space is shown at 4 in the lower part of which is a combustion pot 5, to which is fed a coal or coal slack from the feed hopper 6, through the longitudinal passage 7, in which is positioned a screw conveyor 8. The screw conveyor is driven from a motor 9 upon whose shaft 10 is mounted a

worm 11 meshing with the worm gear 12, which reciprocates a vertical connecting rod 13 which functions a pawl, not shown in the drawings, but which engages the ratchet wheel 14 mounted upon the shaft 8^a, which is an elongation of the conveyor screw shaft. The sprocket wheel and chain mechanism shown at 15 manipulates an automatic dump grate which forms no part of the present invention. On the shaft 10 is also mounted a blower fan 16 which drives air through the aperture 17 discharging it through the duct 18 into the bed of fire contained in the combustion pot through tuyères 19.

In operation the automatic stoker is functioned in the same manner as any common under-feed combustion apparatus, the coal being transferred from the hopper by means of the conveyor screw through the passage 17 and into the bottom of the combustion pot where it forces its way upward into the burning zone, where it is consumed, the ashes overflowing the mouth of the combustion pot.

The control consists of a thermostat diagrammatically shown at 20, which is conveniently positioned in the dwelling at a point where the temperature maintained will more or less control the temperature throughout the house, or, if desired, individual thermostats can be had in the separate rooms of the dwelling and the mechanism complicated accordingly to supply heat at the point desired.

For the purpose of the present invention a single thermostat will suffice. The thermostat operates in connection with the electrical circuit which receives its power from the lines 21 and 22. A cooling of the thermostatic device to a predetermined point will cause a completion of the circuit and contacting of the metal 22^a with the contact point 23, a battery 24 being interposed in the circuit. With the completion of the circuit by the contacting of the members 22^a and 23, the solenoid 25 is energized, which completes the connection between the contacting points 26 and 27. Thus the power from the lines 21 and 22 is conducted through the lines 28 and 29 through the motor 9 and line 30. In this

manner the motor is started and the combustion mechanism put in operation, the drive being transmitted to the screw conveyor and to the blower fan.

5 The operation as suggested is under maximum conditions, or the mechanism is completely stopped at which time the operation is substantially under bank fire conditions.

To supplement this control there is a fluid 10 operated thermostat 31, positioned in the boiler, where it assumes the temperature of the water. The thermostat 31 is set at a predetermined temperature to actuate the diaphragm 32, and this in turn moves the 15 contacting member 33 against or away from the contacting point 34. Assuming that the thermostat 31 is set to actuate the contactor when the water temperature falls below a 20 minimum temperature, when the minimum water temperature is reached the thermostat 31 will function to complete the circuit included within the lines 28, 35 and 30, starting the motor as did the functioning of the 25 thermostat 20.

Attention is called to the fact that the operation of the automatic mechanism preceding the combustion within the furnace when actuated by the minimum temperature 30 control thermostat 31 will be identical to its operation when operated by the thermostat 20. The operation of the thermostat 31, however, is supplementary to the thermostatic control 20 to prevent extinguishment of 35 the fire in the furnace when heat is not required in the dwelling. Furthermore, the operation due to the actuation of the thermostat 31 will cause the mechanism to operate under optimum conditions. That is, the fuel 40 will be supplied at the same rate and air injected to the combustion pot to consume the fuel under the most efficient conditions, rather than producing a slow burning fire which is a normal practice where sufficient combustion 45 is necessary only to keep the fire from being extinguished.

It is understood that the fuel supply and air supply rates are carefully figured to produce the optimum operating conditions when 50 the control device actuates to start the automatic stoker. There is no regulation of drafts as in the common type of furnace, making for operation under varying conditions, none of which are perhaps economically proper and 55 efficient for the fuel which is being used. In the present showing the mechanism is described in connection with a steam boiler, but it will be understood that the secondary control 31 may be positioned in the combustion 60 space, as well as in the boiler, and the minimum temperature governed accordingly.

By this invention, then, economical conditions of combustion are at all times enforced, for when the thermostat 20 in the heated 65 room reaches a predetermined temperature

there is a complete stoppage of the fuel feed mechanism and the forced draft fan. This permits only the burning of the residual fuel, which when consumed would allow the fire to be entirely extinguished, if it were not for the auxiliary control within the combustion pot, which functions when the furnace or the water in the boiler is cooled to a predetermined temperature. This auxiliary control starting the fuel feed and force draft again 75 institutes maximum operation until the temperature in the combustion pot or the water in the boiler is restored to above 100°, or at any other predetermined temperature selected as the minimum temperature. 80

I claim as my invention:

1. A heating system comprising a boiler and combustion pot, an automatic under feed stoker for supplying fuel to said combustion pot, a dual thermostatic control mechanism adapted to operate the stoker, one thermostatic mechanism functioning by variations in the temperature of the interior of the dwelling and the other by predetermined minimum temperature of the fluid temperature in the boiler, to prevent extinguishment of the fire under low heat requirement conditions. 90

2. A force draft furnace for hot water or steam heating systems having a power driven automatic under feed stoking element, adapted to be operated under optimum combustion conditions, a dual thermostatic control mechanism adapted to operate the stoker, one thermostatic mechanism functioning by variations in the temperature of the interior of the dwelling and the other by predetermined minimum temperature of the boiler water to prevent extinguishment of the fire. 95
